(57) **CLAIM**

The ornamental design for a handle light for a grill, as shown and described.

DESCRIPTION

FIG. 1 is a perspective view of the handle light for a grill of the present invention;

FIG. 2 is a top view of the handle light for a grill of the present invention;

FIG. 3 is a front view of the handle light for a grill of the present invention;

FIG. 4 is a right side view of the handle light for a grill of the present invention, the left side being a mirror image thereof;

FIG. 5 is a rear view of the handle light for a grill of the present invention; and,

FIG. 6 is a bottom view of the handle light for a grill of the present invention.

The broken lines shown in the Figures are for illustrative purposes only and form no part of the claimed design.
